(57) CLAIM

I claim the ornamental design for a protective blasting mat, as shown and described.

DESCRIPTION

FIG. 1—is a top and front side perspective view of a protective blasting mat showing my new design;
FIG. 2—is a top plan view thereof;
FIG. 3—is a bottom plan view thereof;
FIG. 4—is a right side view thereof;
FIG. 5—is a left side view thereof;
FIG. 6—is a first end elevational view thereof; and,
FIG. 7—is a second other end elevational view thereof.
A portion of the protective blasting mat is shown broken away in FIGS. 1, 2, 3, 6 and 7 to indicate indeterminate length.
